UNITED STATES PATENT OFFICE.

TILGHMAN HARTLEY, OF SALEM, INDIANA.

STRAW-CUTTER.

SPECIFICATION forming part of Letters Patent No. 231,422, dated August 24, 1880.

Application filed April 17, 1880. (No model.)

To all whom it may concern:

Be it known that I, TILGHMAN HARTLEY, a citizen of the United States, residing at Salem, in the county of Washington and State of Indiana, have invented a new and useful Improvement in Straw-Cutters; and I do hereby declare that the following is a full, clear, and exact description thereof, reference being had to the accompanying drawings and letters of reference marked thereon, forming a part of this specification, in which drawings—

Figure 1 is a perspective view of the straw-cutter from the cutting end of the cutting-box. Fig. 2 is a broken vertical section of the same. Fig. 3 is a detail elevation of the rear or inner side of the cutting-blade and its stock and guides. Fig. 4 is a detail plan view of the device for parting the straw being cut. Fig. 5 is a detail vertical cross-section of the cutting-box and the straw-parting device. Fig. 6 is a detail longitudinal section of the cutting-blade and its stock or supporting-sash.

The nature of my invention will fully appear from the subjoined description, when considered with reference to the accompanying drawings forming a part of this description.

The objects of my invention I accomplish by the mechanism illustrated in the accompanying drawings, in which A indicates the cutter-box of my improved straw-cutter supported upon cross-ties of a supporting-frame represented in perspective view in Fig. 1. The front posts, A' A², of the supporting-frame are rabbeted, as at a, to receive the flanges a' of the metal blade-sash B, and said sash or stock is held in working position by cleats a², secured in any proper manner to the posts A' A²; and when said cleats are applied, as in Fig. 1, they form, in connection with the rabbets a, a groove-way in which the flanges a' work as the blade-sash B is operated up and down in the act of cutting straw or other like substance projected from the box A beneath the cutting or knife blade b.

A fulcrum-pin, as at g, is made to project from the knife-sash B, to which the operating-handle H of the straw-cutter is pivoted and properly secured, as indicated in said figure. One end of this handle is pivoted, as at h, to a rod, h', whose lower end is pivotally secured in the post A², so that when the handle H is

worked in the act of cutting straw the rod h will oscillate in accord with the movements of the handle, at the same time affording it a proper support and steadiness of action.

55

The knife-sash B, I construct of a single piece of cast metal having its body portions b' form an obtuse angle, as at b², and when the cutting-blade b is secured to the inner side of said sash B, as shown in the figures, the line 60 of cut of the cutting-edge of the knife b, both at the right and left hand of said obtuse angle b², will be at an angle of forty-five degrees to the horizontal line or plane of projection of the straw from the box A, and thus cut the straw 65 on such angle.

The cutting of the straw on an angle of forty-five degrees, as stated, not only requires less power of the operator to be applied to the handle H than would be the case were the cut 70 made directly across or at right angles with the straw, while at the same time the oblique limbs of the knife-blade b, on either side of the angle b², possess a capacity for cutting just so much more straw at a single stroke as the 75 united length of said limbs exceed the width of the cutter-box A at the dotted line x in Fig. 5. To facilitate this oblique cut of the straw on either side of the angle b² of the blade b, I provide the cutter-box with a cast-metal 80 plate, C, the outline of which is shown in plan view, Fig. 4. The forward end portion, c c' c, of said plate is constructed to exactly register with the cutting-edge of the knife-blade b when set in working position, as in Figs. 1 and 2. 85 Its sides, as at c², are formed to abut against the inside surfaces of the side pieces, e, of the cutter-box A, and so be held from lateral play, and thence it tapers down to its extreme rear portion, as at c³. Near its rear end, c³, it is perforated for the insertion of a screw, s, which 90 screws into the bottom piece, e', of the box A, and by means of which it may be fastened fixedly in the position indicated in Figs. 1 and 2.

The perforation through the plate C may conform to the size of the shank of the screw s, and thus hold the plate C in only one given position; or the perforation may be slightly elongated, as signified at s', and so admit of the longitudinal forward adjustment of the plate 100 C as the cutting-face of the knife b wears away.

The upper surface of the plate C, as shown

at c^3 , Figs. 1 and 5, slopes away from its longitudinal central line, c^4 , and downwardly toward and to the sides of the cutter-box, so that when the straw is pressed upon the surface c^3 by the action of the knife-blade b in the act of cutting the sloping or curved form of said surface on either side of the longitudinal central line, c^4 , will hold the straw firmly against the upwardly-inclined edge of the knife-blade, and thus effect a shearing cut of the straw.

Figs. 1, 2, and 5 show a metal guide-cap, D, secured to the upper edges of the side pieces, $c\ e$, of the box A. This cap is of angular form, as shown in Figs. 2 and 5, and has its forward 15 end sloping downward, so as to press the straw toward the plate C during the operation of the machine. The extreme forward angular portions, ff , of this cap are formed so as to abut against the inner surface of the portions b' of the blade-sash B, and thus also serve to steady the action of the sash during its up and down movements.

When it becomes necessary to remove the sash B to grind the blade b , its removal can be effected by simply detaching the handle H from its fulcrum-pin g , and then raising the sash B up out of its bearings in the posts A' A².

The peculiar formation of the plate C serves to part the straw to the cutting action of the knife-blade b , and so distribute the mass of straw over the curved surface c^3 and beneath the cutting-edge of the blade b on either side of its angle b^2 , thereby producing ease in cutting, while a large amount of straw can be cut 35 at a single stroke of the sash B, during which

action the spreading of the straw on either side of the line c^4 of the plate C is insured by the angular form of the compressing-cap D, acting conjointly with said plate C.

The cutting-blade b is made of a single piece 40 of metal, and centrally of its length is formed with an obtuse angle to correspond with the obtuse angle, as at b^2 , formed in the blade-sash B, and for the purpose of applying the blade to the sash the latter has a portion of 45 its inner face cut away, as indicated in Fig. 6, so that the blade may be seated therein and the blade secured in position to the sash by screws. The blade and the sash when thus secured, and in the position as indicated in Fig. 50 3, will then form such an adjustment that the working-face of the blade and the inner surface of the body portions b' of the sash will be flush with each other.

I claim—

1. The combination of the angular cap D, the angular sash B, the angular blade b , and the plate C, substantially as and for the purpose described.

2. The metal plate C, provided with the 60 sloping surface c^3 on each side of its longitudinal center, and with its extreme forward end, $c\ c'\ c$, formed to register with the interior surface of the sash B and its cutting-blade b , substantially as and for the purpose described.

.TILGHMAN HARTLEY.
